SAFETY RAZOR

Ralph E. Thompson, Brookline, and Angus A. Martin, Dorchester, Mass.

Application July 31, 1937, Serial No. 156,708

16 Claims. (Cl. 30—74.1)

This invention relates to safety razors and has for its primary object the development of a combined safety razor and blade of simplified construction and in which the blade is automatically located and held to accurate shaving position upon closing movement of the razor. In its preferred form the razor comprises primarily two portions or halves pivoted together and movable about the pivot to open and closed positions. 10 In the open position the razor permits the free insertion and removal of a blade, and parts carried by and preferably integral with the pivoted portions serve to locate and securely hold the blade in proper position for shaving. The two parts may be, and preferably are, of identical construction whereby the same can be manufactured with great economy. The invention is particularly applicable to, though not necessarily limited to, a double edged razor of the "Gillette" 20 type and for convenience we herein disclose the invention in such form.

The pivoted portions of the razor are adapted to receive and support the blade, and carried by one or both of such portions are arms arranged 25 to engage against the inner face of the blade and press it securely against said portions when the razor is closed. These arms are so arranged that when they are in open position they are in such substantially parallel alignment that the 30 blade, which is apertured therefor, may be placed thereover and removed therefrom. Such construction is economical to produce, provides for convenient insertion and removal of blades and serves automatically to locate and hold the blade 35 securely and accurately for shaving.

The blade receiving and securing arms may be formed in a single group arranged to pass through a slot in the blade or may be arranged in spaced relation to pass through spaced apertures in the blade. Furthermore, in accordance 40 with another feature of the invention, the blade may have other apertures therethrough and the arms can be provided with lugs for engaging within these apertures to automatically locate 45 the blade in accurate shaving position upon closing movement of the razor. The razor may be of the single or double edge type and such apertures and arms may be provided and so located as to perform the function resulting from the 50 invention. In the preferred form of the invention, employing a double edged blade, the blade is apertured on both sides of its medial line and all the arms are provided with V-shaped lugs at their free ends to engage within these apertures 55 and automatically locate the blade transversely.

as the razor is closed, it being understood that the shaving exposure of the sharp edge is determined by such location of the blade. The production of an improved razor and blade combination embodying these improvements comprises another object of the invention. 5

These and other features of the invention are best understood and appreciated from the following description of preferred embodiments thereof, selected for purposes of illustration and shown 10 in the accompanying drawings in which,

Fig. 1 is a side elevation of a safety razor embodying one form of our invention,

Fig. 2 is an edge elevation thereof,

Fig. 3 is a fragmentary view of the razor in 15 longitudinal section taken on line 3—3 of Fig. 1,

Fig. 4 is a fragmentary sectional view taken on line 4—4 of Fig. 3,

Fig. 5 is a handle end elevation of the razor,

Fig. 6 is a longitudinal sectional view of the 20 razor in open position,

Fig. 7 is a head end elevation, partially broken away,

Fig. 8 is a detailed view showing one form of 25 pivot,

Fig. 9 is a perspective view of a blade for the 30 razor,

Fig. 10 is a side elevation of a modified form 35 of the invention,

Fig. 11 is a fragmentary edge view thereof, 30

Fig. 12 is a fragmentary view of the razor in 40 longitudinal section taken on the line 12—12 of Fig. 10,

Fig. 13 is a fragmentary view of the razor and 45 blade in open position, taken on line 13—13 of Fig. 14,

Fig. 14 is a sectional view taken on line 14—14 of Fig. 13,

Fig. 15 is a head end elevation of the razor and 50 blade,

Fig. 16 is an enlarged detailed view showing the 55 action of one of the blade locating lugs,

Fig. 17 is a perspective view of the blade co- 60 operating with this form of the invention.

Our invention is particularly applicable to a 45 razor of the double edged "Gillette" type and in the accompanying drawings we have illustrated two forms thereof. The form shown in Figs. 1—9 will first be described.

This razor primarily comprises two pieces 10 50 and 11 pivoted together at 12. As illustrated, the two pieces 10 and 11 are of like construction and each comprises a handle portion 14 and a blade holding portion 15, the pieces being preferably of die-formed sheet metal for economical manu- 55

facture. The two head portions are pivoted together adjacent to their ends and intermediate of such ends each such portion is cut away to provide a plurality of relatively spaced fingers 16, the fingers being bent inwardly as illustrated in Figs. 3 and 6. When the two pieces are pivoted together the fingers thereof are in alternate arrangement between the two pivots and are located inwardly of the head.

10 Each head portion 15 is U-shaped and this shape is supported by connecting straps 18 integral with and bent downwardly from the outer leg of the U and in overlapping contact at 19 with the inner leg. The pivots may be formed 15 by extending pins 12 through eyes 20 turned up integral with the head portions or each pivot pin may be constructed as an integral part 22 of one head as illustrated in Fig. 8. Each head portion 15 is slotted at 24 adjacent to the apex 20 of the U and guard teeth 25 are formed along one edge thereof at this slot.

The blade 26 is of the "Gillette" type, having opposed sharpened edges 28 and slotted in its central portion at 30. When the two parts of 25 the razor are opened from the closed position of Figs. 2 and 3, the fingers 16 pivot toward each other and, when the parts are open nearly to the position of Fig. 6 the fingers are substantially in parallel alignment and adapted to receive the 30 blade thereover, the fingers passing through the slot 30. The length of this slot is substantially the length of the combined fingers, thereby locating the blade longitudinally. When the parts are in the open position of Fig. 6, the inclined 35 portions of the fingers engage the two longitudinal edges 32 of the slot 30, and thus locate the blade transversely. As the parts are brought to the fully closed position, the free end portions of the fingers engage the inner face of the blade 40 and flex it into firm contact with the opposing surfaces of the head portions 15, to the position 45 illustrated in Fig. 3.

It is particularly pointed out that in the fully closed position of Fig. 3, the blade is properly 45 located and held firmly in the razor with the sharp edges thereof exposed along the slots 24 and in position protected by the guard teeth 25. It is furthermore noted that the construction of 50 the razor is such that the blade is automatically secured in shaving position merely by the closing action of the two parts. When the portions are in fully opened position of Fig. 6 the blade is held in freely exposed position on the razor in 55 which position it can be rinsed without interference.

While the razor may be held in the closed position by any suitable means, we have herein illustrated a novel latch integral with the handle parts for that purpose. This latch comprises 60 two laterally extending and cooperating detents 34 at the free ends of the handles. The inner edges of these detents are so arranged (Fig. 5) that opening of the razor crowds the handles apart, the result being that the handles and detents normally remain locked in the closed position of Fig. 5.

Two shoulders 36 are provided respectively on the two handle pieces and in such arrangement that pressure brought thereagainst in the opposing 70 directions indicated by the arrows in Fig. 2 forces the handle sections and their detents apart. The razor can be conveniently opened by holding the head with the left hand while grasping and pressing these shoulders as indicated 75 with the fingers of the right hand.

The razor illustrated in Figs. 10-17 comprises two pieces 40 and 41 pivoted together at 42. These two pieces are of like construction and each comprises a handle portion 44 and a blade holding head portion 45. Each head portion 45 is U-shaped and this shape is supported by connecting straps 46 integral with and bent downwardly from the outer leg of the U and into overlapping contact with the inner leg at 48. Each portion 45 is also slotted at 50 adjacent to the apex 10 of the U and guard teeth 52 are formed along one edge of each head portion on this slot.

The outer leg of each portion 45 comprises a blade supporting bar 54, and extending beyond the free edge 55 of each bar are three arms 56, 15 all facing one end of the bar. The intermediate portion of each arm is thickened and perforated to receive the pivot pin 42 which connects the two pieces, the surfaces 57 facing each other in 20 cooperating relation when the two bars are assembled. When the two parts are brought substantially to the point of Fig. 14, the arms 56 cooperate to form three studs for receiving the 25 blade.

The purpose of our invention herein is not only to provide a relatively simple two piece 30 razor, but furthermore, to provide a combined razor and blade wherein the blade will be accurately positioned and firmly supported in the 35 razor merely by the closing action of the razor. We accomplish this object by so forming the 40 blade and razor that the latter automatically cooperates with the former to perform these functions when the razor is brought from the open to 45 the closed position.

The blade 60 is of the "Gillette" type, having 50 opposed sharp edges 62 and perforated in its central portion at 64 to receive the studs provided by the arms 56 when the razor parts are in the 55 position of Fig. 14. The arms are also provided with shoulders 66 limiting outward movement on the studs as is also illustrated in Fig. 14. When the razor is moved in closing direction from the open position of Fig. 14 the arms move downwardly toward the inner face of the blade while the bars 54 move upwardly toward the outer face 60 of the blade.

It is desirable to locate the blade accurately 65 in the transverse direction to give proper shaving exposure of its sharpened edges when the razor is fully closed, and to this end we provide locating lugs 68 on the free ends of the arms and 70 cooperating apertures 70 in the blade. The lugs are preferably V-shaped to engage the edges of the apertures and the bars 54 are recessed at 72 to provide clearance for the lugs. It will now be 75 apparent that as the razor is brought to the closed position, the lugs enter the apertures 70 and thereby automatically locate the blade exactly to the transverse position predetermined by the location of the lugs and apertures. Furthermore, when the razor is fully closed, the blade is held flexed between the arms and the inner supporting surface provided by the bars 54.

Having thus described our invention, what we claim as new and desire to secure by Letters Patent of the United States is:

1. A safety razor comprising two cooperating 70 handle portions and a blade holding head, the head comprising two portions pivoted together on a common axis and respectively integral with the two handle portions, each head portion having a surface for engaging the outer face of a blade and one head portion having means integral 75

therewith for engaging the inner face of the blade and pressing it outwardly toward the head surfaces when the razor is closed.

2. A safety razor comprising two cooperating handle portions and a blade holding head, the head comprising two portions pivoted directly to each other and respectively integral with the two handle portions, the axis of said pivot extending longitudinally of the head and passing substantially through the longitudinal axis of the handle when the razor is in closed position, and latch means for holding the razor closed.

3. A safety razor comprising two cooperating handle portions and a blade holding head, the head comprising two portions pivoted together on a common axis and respectively integral with the two handle portions, the head portions having means integral therewith and extending beyond the pivot axis for engaging the inner face of a blade supported at its outer face by both portions of the head when the razor is closed.

4. A safety razor of the "Gillette" type comprising two cooperating handle portions and a blade holding head, the head having guard means along each lateral edge and comprising two portions pivoted directly to each other and respectively integral with the two handle portions, means carried by one head portion for engaging the inner face of a double-edged blade supported at its outer face by both portions of the head when the razor is closed and having sharpened edges extending along the guard means, and latch means for holding the razor closed.

5. A safety razor of the "Gillette" type comprising two cooperating handle portions and a blade holding head, the head having guard means along each lateral edge and comprising two portions pivoted together on a common axis and respectively integral with the two handle portions, alternately arranged teeth in side to side relation integral with the head portions and extending beyond the pivot axis for engaging the inner face of a double-edged blade supported at its outer face by both portions of the head when the razor is closed and having sharpened edges extending along the guard means, and latch means for holding the razor closed.

6. A safety razor comprising a blade holding head and a pair of handle portions attached to said head and independently movable into engagement with each other to provide a handle, and latch means for holding the handle portions in engagement, said means comprising a laterally extending detent on the free end of each portion arranged to engage in a recess in the other portion, the inner edges of the detents engaging with each and shaped to crowd the handle sections laterally outward in opposite directions when the sections are opened from the closed position.

7. The razor defined in claim 6, plus shoulders on the two handle portions so arranged that pressure brought there against forces the portions from the closed position to the open position.

8. A safety razor comprising two halves pivoted directly to each other, said halves being of like shape and construction and providing a blade holding head adjacent to the pivot, means carried by one of the halves and cooperating with the other half to grip a blade therebetween and hold it in shaving position at said head when the razor is closed, the halves being pivotal to an open position permitting the insertion and removal of a

blade, and means for securing the halves in closed position.

9. In combination, a safety razor comprising a blade holding head portion provided with a guard for the sharp edge of a blade, a blade mounted on such portion and having an aperture therethrough located a predetermined distance from its sharp edge, a second portion pivoted to the first portion and movable about the pivot to an open position permitting the insertion and removal of the blade, and means carried by the second portion and movable therewith into the aperture when moving the portions to closed position whereby to locate and hold the blade with its sharp edge in predetermined transverse position relative to the guard.

10. The combination defined in claim 9 wherein in the blade is provided with a plurality of apertures spaced longitudinally of the blade and wherein said means comprises a plurality of projections carried by said second portion and movable therewith into the apertures to locate and hold the blade positioned in transverse direction relative to the guard.

11. In combination, a safety razor comprising two portions pivoted directly to each other and each having a guard for the sharp edge of a blade, a double edged blade mounted on the portions with a sharp edge adjacent to each guard and having a plurality of apertures therethrough located predetermined distances from the two sharp edges, and projection carried by one portion for engaging within one of said apertures when moving the portions to closed position whereby to locate and hold the blade with one sharp edge in predetermined position relative to its guard.

12. In combination, a safety razor comprising two portions pivoted to each other along a medial line and each having a blade supporting surface on one side of the pivot, a double edged and apertured blade mounted on said portions, arms projecting from both portions and through the blade on the other side of the pivot and lugs on certain of the arms engageable within the blade apertures when moving the portions to closed position thereby locating the blade transversely.

13. In combination, a safety razor comprising two portions pivoted to each other along a medial line and each having a blade supporting surface on one side of the pivot, a double edged blade mounted on said portions, and a plurality of pairs of arms projecting from the portions and through the blade at the other sides of the pivot and engaging the inner face of the blade and gripping it between the arms and the blade supporting surfaces.

14. In combination, a safety razor comprising two portions pivoted to each other along a medial line and each having a blade supporting surface on one side of the pivot, a double edged and apertured blade mounted on said portions, and a plurality of pairs of arms projecting from the portions and through the blade at the other sides of the pivot and having lugs on their free ends engageable within the blade apertures to locate the blade transversely.

15. In combination, a safety razor comprising two portions each having a plurality of arms projecting from one edge thereof, means pivoting the portions together at said arms, a blade apertured to receive the arms therethrough when the razor is in open position with the arms on the two portions substantially in parallel alignment, the blade having other apertures there-

- through, and V-shaped lugs carried by certain of said arms for engaging in said other apertures to locate the blade transversely and hold it in shaving position when the razor is closed.
5. 16. In combination, a safety razor comprising two portions each having a plurality of arms projecting from one edge thereof, means pivoting the portions together at said arms with one arm of each portion cooperating with an arm of the other portion, a blade apertured along its medial line to receive the arms therethrough when the

razor is in open position and the arms of the two portions are substantially in parallel alignment, the blade having other apertures therethrough at opposite sides of the medial line, and lugs carried by said arms for engaging in said other apertures to locate the blade transversely and hold it in shaving position when the razor is closed. 5
